LIGHT STANDARD OR SIMILAR ARTICLE

Robert Willoughby Selden, Seattle, Wash., assignor to Weyerhaeuser Company, Tacoma, Wash.

Filed Sept. 21, 1970, Ser. No. 25,079

Term of patent 14 years

Int. Cl. D26—03

U.S. Cl. D48—20

FIG. 1 is a front elevational view of a light standard or similar article illustrating my new design.

FIG. 2 is a top plan view thereof.

FIG. 3 is a fragmentary rear elevational view thereof.

FIG. 4 is an enlarged cross-sectional view taken on line 4—4 of FIG. 1.

FIG. 5 is an enlarged cross-sectional view taken along line 5—5 of FIG. 3.

FIG. 6 is a front elevational view of the second embodiment of my design.

FIG. 7 is a top plan view thereof.

FIG. 8 is a fragmentary rear elevational view thereof.

FIG. 9 is an enlarged cross-sectional view taken on line 9—9 of FIG. 6.

FIG. 10 is an enlarged cross-sectional view taken along line 10—10 of FIG. 8.

FIGS. 11—13 are enlarged cross-sectional views of additional embodiments of my new design, the cross-section being taken on the embodiments on a plane identical to lines 5—5 of FIG. 3 and 10—10 of FIG. 8, it being understood that these embodiments differ from FIGS. 3 and 8 only in cross-section of the uprights.

The lamps are shown in broken lines in FIGS. 1—3 and 6—8 for illustrative purposes only. The lamp standard is fragmentally shown in FIGS. 3 and 8 for convenience of illustration.

I claim:

The ornamental design of a light standard or similar article, as shown and described.
